UNITED STATES PATENT OFFICE.

ARTHUR J. MASON, OF CHICAGO, ILLINOIS, ASSIGNOR OF ONE-HALF TO
FRANK K. HOOVER, OF CHICAGO, ILLINOIS.

EXCAVATING APPARATUS.

SPECIFICATION forming part of Letters Patent No. 729,195, dated May 26, 1903.

Application filed November 22, 1902. Serial No. 132,362. (No model.)

To all whom it may concern:

Be it known that I, ARTHUR J. MASON, a citizen of the United States, residing at Chicago, in the county of Cook and State of Illinois, have invented certain new and useful Improvements in Excavating Apparatus, of which the following is a specification.

My invention relates to improvements in excavating apparatus of that class or type commonly known as "clam-shell" buckets, which are ordinarily swung from a derrick-boom or other support and by means of power transferred from a hoisting-engine by cables or chains may at the will of the operator be lowered or raised, opened or shut, and so constructed and arranged that in their closing operations they may grasp the material to be handled, whether earth, stone, coal, ore, lumber, or any other material. In Letters Patent granted July 30, 1901, to Frank K. Hoover and Arthur J. Mason, No. 679,475, is shown a scoop or bucket of this type, upon which my present invention is more particularly based, although it is equally applicable to any other form of scoop or bucket characterized by the provision of main side arms or levers so formed and arranged in the apparatus as to present parts or portions which come together in the relative movement of the arms, while other portions simultaneously diverge, and vice versa. In the device shown in the aforesaid patent a somewhat elaborate and complicated arrangement of devices in the general nature of oppositely-disposed toggles is employed in connection with the opening-lines to effect the opening of the bucket, the parts of which are connected to crossed principal lever-arms.

My present invention has to do with a greatly-simplified form and construction of opening means which does away entirely with the toggle devices applied to the opposite sides of the bucket, as shown and described in the aforesaid patent.

In the accompanying drawings, which represent an illustrative embodiment of my invention, Figure 1 represents a side elevation of the apparatus, the closed position of the trays and their operating mechanism being shown in full lines and the open position of the same being indicated in dotted lines; and

Fig. 2 represents an end elevation of the parts closed.

Describing first those parts of the apparatus which are old and disclosed in the patent above referred to, 1 designates the trays, the form of which is plainly shown in Fig. 1, these trays being oppositely disposed and having their cutting edges arranged adjacent and in opposition to each other, as is usual in this class of scoops.

2 indicates a pair of principal lever-arms pivotally mounted at their upper ends upon a central shaft 3 and at their lower ends pivotally connected, as at 4, with the trays 1 near the forward ends of the latter. These arms 2 have the curved and substantially S-shaped formation shown in the drawings, whereby it will be observed that they cross each other between their points of pivotal connection 70 with each other and with the trays somewhat after the fashion of a pair of shears. The heel or rear portions of the trays are indicated at 5 in the form of a pair of short rearwardly-extending arms, and 6 indicates a pair of auxiliary arms, which are pivoted at their lower or outer ends to the heels 5 of the trays and at their inner or upper ends to the proximate or adjacent portions of the oppositely-disposed principal lever-arms 2, respectively. 75 By reason of this peculiar form of the principal lever-arms and the described connection and arrangement of the auxiliary arms 6 relatively to the trays and the principal lever-arms 2 a very wide opening and a peculiar 80 travel and operation of the trays is secured, which is fully set forth and described in the aforesaid patent and constitutes no feature of my present invention.

The means for closing the trays and causing the latter to gather their load consists of a closing-cable 7, the upper end of which is in practice passed over a derrick-boom to a suitable winding-drum or equivalent hoisting apparatus, while the lower end of the cable is 90 led around a suitable guide-sheave 8, mounted in a bracket or hanger 9, hung on the main pivotal shaft 3, said cable passing thence around suitable guide-sheaves 10 and 11 on the principal lever-arms near the lower ends 95 thereof and below their point of crossing, the end of the cable being secured to one of said 100

arms. From the described manner of connecting the closing-cable to the arms it will be observed that the weight of the apparatus applied to the closing-cable will automatically 5 tend to draw together the lower ends of the principal lever-arms, thereby bringing the cutting and gathering edges of the trays into contact and will hold said trays securely in closed position during the transfer of the 10 load.

Referring now to the means for effecting the automatic opening of the trays when the weight of the apparatus is applied to the opening-lines, 12 indicates a transverse shaft 15 extending between and connecting the upper portions of corresponding members of the principal lever-arms above their point of crossing. On each of said shafts 12, on either side of the apparatus, is mounted a pair of 20 guide-sheaves 13 and 14, respectively, while on each end of the main pivotal shaft 3 is hung a hanger or bracket 15, in which is mounted a guide-sheave 16, corresponding in function to the guide-sheave 8 for the closing- 25 line.

17 indicates the opening-line on each side of the apparatus, the upper end of which extends over the derrick-boom to a suitable winding-drum or equivalent lowering and 30 hoisting apparatus, the lower end of said opening-line passing in contact with the guide-sheave 16, thence down and around the guide-sheaves 13 or 14, as the case may be, and being secured at its end to one of the transverse 35 shafts 12.

It is obvious from the described connection of the opening-line to the principal lever-arms of the scoop that the weight of the latter when applied to the opening-line will tend 40 to automatically draw together the upper portions of the principal lever-arms lying above their point of crossing, which by virtue of the fact that said arms intersect each other between their pivotal connection with the shaft 45 3 and their connections with their respective trays effects a simultaneous separation and divergence of the lower portions of the principal lever-arms and of the trays directly connected thereto.

50 It will of course be understood that the described parts and their relative connections as shown in side elevation in Fig. 1 and as hereinabove largely described in the singular are exactly duplicated on the opposite 55 sides of the apparatus, said parts on the opposite sides of the device being rigidly united transversely through the bodies of the trays themselves, which of course are integral from side to side, and through the main pivotal 60 shaft 3, as well as through the intermediate transverse shafts 12, where the latter are employed, as herein shown. It will be obvious, however, that in some forms of scoops adapted for light work and not subjected to the 65 severest strains the intermediate transverse shafts 12 might be dispensed with, the auxiliary arms 6 and the guide-sheaves 13 and

14 being pivotally and rotatably mounted directly on the inner or outer faces of the principal lever-arms.

70 From the foregoing it will be seen that the principle of my invention resides in the employment of principal lever-arms so formed and related to each other and so connected with the main pivotal shaft and their respective buckets as that while certain respective parts of these arms swing outwardly in the opening or closing operation other respective parts of said arms simultaneously swing inwardly in the same operations and the connecting of one of said respective portions of the arms so as to be drawn together by the closing-lines and the similar connecting of the other respective parts of said arms so as to be drawn together by the opening-lines. 80 I do not, therefore, limit my invention to the particular form or arrangement of the mechanism shown in the drawings, which is illustrative merely of my invention, so long as the underlying principle thereof as above 90 defined is retained.

I claim—

1. In an excavating apparatus of the type described, the combination with a pair of crossed principal lever-arms, and trays connected thereto at their lower ends, of an opening-line extending between and connecting said arms above their crossing-point and tending to draw the lower portions of the arms and the trays apart, substantially as described.

2. In an excavating apparatus of the type described, the combination with a pair of crossed principal lever-arms, and trays connected thereto, of a closing-line extending between said arms on one side of their crossing-point and operating thereon to draw the trays together, and an opening-line extending between said arms on the other side of said crossing-point and tending to draw the trays apart, substantially as described.

3. In an excavating apparatus of the type described, the combination with a pair of crossed principal lever-arms pivotally united at their upper ends, and trays connected thereto at their lower ends, of a closing-line connecting said arms on one side of their crossing-point and operating thereon to draw the trays together, and an opening-line connecting said arms on the other side of their crossing-point and tending to draw the trays apart, substantially as described.

4. In an excavating apparatus of the type described, the combination with a pair of crossed principal lever-arms pivotally united at their upper ends, and trays connected thereto at their lower ends, of auxiliary arms pivotally connected with the trays and with said principal lever-arms, a closing-line connecting said principal arms below their crossing-point and operating to draw the lower portions of said arms and the trays together, and an opening-line connecting said arms above their crossing-point and tending to

draw the upper portions of said arms together and the trays apart, substantially as described.

5. In an excavating apparatus of the type described, the combination with a pair of crossed principal lever-arms pivotally united at their upper ends, and trays connected thereto at their lower ends, of auxiliary arms pivotally connected with said trays in rear of the connection of the principal arms thereto and to the opposite principal arms, a closing-line connecting said principal arms below their crossing-point, and an opening-line connecting said arms above their crossing-point, substantially as described.

6. In an excavating apparatus of the type described, the combination with a pair of substantially S-shaped principal lever-arms

pivotaly united at their upper ends and crossing each other intermediate their ends, of trays connected thereto at their lower ends, auxiliary arms pivotally connected with said trays in rear of the points of connection of the principal arms therewith and with the opposite principal lever-arms above their point of crossing, a closing-line connected to and guided around suitable sheaves on said principal arms below their crossing-point, and an opening-line connected to and guided around suitable sheaves on said principal lever-arms above their crossing-point, substantially as described.

ARTHUR J. MASON.
